(57) **CLAIM**

The ornamental design for a soft cooler bag, as shown and described.

DESCRIPTION

FIG. 1 is a perspective view of a soft cooler bag, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view of the soft cooler bag with the top open.
 In FIG. 7, the broken line and areas within and immediately adjacent to the solid line defining the outside edge of the bottom of the article depict portions of the soft cooler bag that form no part of the claimed design.

1 Claim, 8 Drawing Sheets
